UNITED STATES PATENT OFFICE

ALVAN V. BURCH, OF EVANSVILLE, INDIANA

DISK BARRING-OFF ATTACHMENT FOR CULTIVATORS

Application filed January 13, 1930. Serial No. 420,445.

The present invention relates to a disk barring off attachment adapted to be substituted for a shovel on a walking or riding shovel cultivator.

5 My object is to provide an improved mounting for the disk, whereby increased rigidity is obtained, with adaptability for adjustment of the securing means to compensate for any form of shank employed and to enable the 10 disk to be positioned at the proper angle and in the proper relationship to the cultivator, to throw the dirt as the operator may see fit and to insure clean and adequate cutting of the trash which it is desired to cut up and to 15 turn under the soil.

To the usual cultivator foot carried by a shank secured to the machine, is connected an improved disk carrier, means being provided for locking the disk carrier in different positions of angularity in respect to the ordinary shovel foot. An improved mounting for the disk is secured to the foot by bolts passing through the slot in the foot, the relationship of the mounting and the foot being such that 25 the mounting may be adjusted to different angles in relation to the foot and secured in the desired position. The mounting has a tapered thimble and the disk has attached thereto a stub shaft or gudgeon whose head 30 is riveted to the inner face of the disk and whose shank is mounted in the thimble, the parts being connected by a bolt running through the gudgeon and having a nut and washer bearing against the thimble.

35 Thus, the disk is mounted so that it will freely turn in the thimble of the disk mounting and the mounting can be shifted in relation to the foot to dispose the disk at different angles so that the dirt may be thrown as the operator desires and, in addition, the foot itself can be swung on the usual shovel shank to which it is pivoted and secured where adjusted.

40 Another embodiment of the invention comprises a cylindrical foot on which the disk carrier is mounted to turn so that the disk may be disposed at the proper angle to accomplish the desired results.

45 With my improvements, the disk barring

off attachment may be readily substituted for shovels in an ordinary shovel cultivator.

In the accompanying drawing:

Figure 1 is a perspective view showing my improvement applied to a cultivator, the 55 shovels having been removed;

Fig. 2 is a detail side view of the shank, foot and the attachment carrying a disk;

Fig. 3 is a front view of the usual shank and foot alone, the carrier and disk having 60 been removed;

Fig. 4 is a vertical section through the disk and the means for mounting it, the shank and foot being broken away;

Fig. 5 is a plan view of the mounting; 65

Fig. 6 is a detail section showing the manner in which the mounting is mounted on the foot, and

Figs. 7 and 8 are detail views of a modification employing a tubular or cylindrical foot. 70

A cultivator of ordinary construction is shown, generally, at 1, being provided with the usual cross heads 2 that carry the shanks or standards for the shovels, not shown, which are usually employed. 75

My disk barring off attachments are intended to be substituted for the shovels but as the construction is the same in each instance, a description of one attachment will suffice. The shank is shown at 3, being suitably secured to the cross head. 80

The foot 4 which is pivoted to the shank at 5 so that it is rockably mounted thereon, has a bolt and slot connection 6 by which it may be secured in the position to which it is tilted. 85

My improved mounting 8 is dished or concaved, as shown at 9 and the upper face of the foot 4 is rounded, as shown at 10, to form a seat for the mounting 8 so that the mounting 90 can be adjusted in general cross-wise relationship to the carrier.

Bolts 11 secure the mounting 8 to the foot, said bolts passing through the slot 7 and also through elongated slots 12 in the mounting 8. The slots 12, in connection with the bolts 11, enable the disk 13 to be changed as to angular relationship to the foot 4 in a manner adapting said disks to be so disposed 95 that they can be adjusted to throw the dirt 100

as the operator sees fit and to insure clean cutting of the trash.

The disk 13 has riveted thereto at 14 a stub-shaft or gudgeon 15, which extends through a hole in the disk and is mounted to turn in a tapered thimble 16 which is integral with the mounting 8 and arranged cross-wise thereof and angularly thereto. A bolt 17, which extends through a bore in the stub-shaft or gudgeon 15, carries a nut and washer 18 which bear against the smaller end of the thimble 16. Thus, the disk is rotatably mounted.

In the modification shown in Figs. 7, 8, the foot 4' is of round stock and there is rotatably mounted thereon the mounting 8' which may be clamped to the stock in any desired adjusted position by bolts 11'. The thimble 16' which is an integral part of the mounting 8', serves as a bearing for the gudgeon 15 of the disk 13 in the manner hereinbefore described. The mounting 4' can be turned or adjusted to position the disk 13 to throw the dirt as the operator may see fit.

What I claim is:

1. In a cultivator, the combination with a shank, of a foot adjustably connected to said shank, a cultivator disk-carrier for adjustably connecting the disk to the cultivator foot to enable said disk to be swung to different positions on the foot, comprising a clamping disk-mounting provided with a thimble, a disk, means by which the disk is journaled in said thimble, and clamping bolts and nuts by which the disk-mounting is adjustably clamped against the foot, said bolts extending clear through the disk mounting and having their heads exposed and located on one side of the disk mounting and their nuts exposed on the other side of said disk mounting.

2. A cultivator disk-carrier for adjustably connecting the disk to a cultivator foot to enable the disk to be swung to different positions on the foot, comprising a clamping disk-mounting provided with a thimble, a disk, means by which the disk is journaled in said thimble, said disk-mounting being provided with slots, and clamping bolts extending through said slots and provided with nuts, said bolts and nuts constituting means by which the disk-mounting is clamped against the foot with adaptability for swinging adjustment in relation to the foot.

3. In a cultivator, the combination with a shank, of a slotted foot adjustably connected to said shank, a cultivator-disk carrier for adjustably connecting the disk to the slotted cultivator foot to enable the disk to be adjusted to different positions on said foot, comprising a clamping disk-mounting provided with a thimble, a disk, means by which the disk is journaled in said thimble, and clamping bolts extending through the disk-mounting and clear through the slot in said foot and provided with nuts, whereby the

disk-mounting may be clamped to the foot, said bolts having their heads exposed on one side of the disk mounting, and said nuts being exposed on the exterior of the slotted post.

4. A cultivator-disk carrier for adjustably connecting the disk to a slotted cultivator foot to enable the disk to be adjusted to different positions on the foot, comprising a clamping disk-mounting provided with a thimble, a disk, means by which the disk is journaled in said thimble, said disk-mounting having slots, and clamping bolts extending through said slots and through the slotted foot and provided with nuts, whereby the disk-mounting may be adjusted in relation to the foot and clamped in its adjusted position to vary the angle of the disk as desired.

In testimony whereof I affix my signature.
